Patented Sept. 7, 1926.

Des. 71,038

UNITED STATES PATENT OFFICE.

WESTERN UNDERWOOD, OF LOS ANGELES, CALIFORNIA.

DESIGN FOR A SIGN FOR LIGHTING POSTS.

Application filed May 6, 1926. Serial No. 17,583. Term of patent 3½ years.

To all whom it may concern:

Be it known that I, WESTERN UNDERWOOD, a citizen of the United States, residing at Los Angeles, in the county of Los Angeles and State of California, have invented a new and original and ornamental Design for Sign for Lighting Posts, of which the following is a specification, reference being had to the accompanying drawing, forming a part thereof.

The figure is a perspective view of a sign for lighting posts showing my new design.

I claim:

The ornamental design for a sign for lighting posts, as shown.

WESTERN UNDERWOOD.
